UNITED STATES PATENT OFFICE

2,094,030

LOCKSTITCH SHOE SEWING MACHINE

Laurence E. Topham, Wenham, Mass., assignor
to United Shoe Machinery Corporation, Paterson, N. J., a corporation of New Jersey

Application March 23, 1932, Serial No. 600,654
Renewed November 5, 1936

41 Claims. (Cl. 112—36)

The present invention relates to lockstitch sewing machines which employ a hook needle to draw loops of needle thread through the work, and more particularly, to sole sewing machines of the so-called McKay type, the hook needle of which is straight, and the work support of which consists of a rotatable horn arranged to extend within the shoe, and provided at its tip with a needle threading device for laying the thread in the hook of the needle.

The object of the invention is to improve generally the operation of lockstitch shoe sewing machines of the McKay type, employing a rotary shoe supporting horn and a needle threading device in the horn. The usual practice in ordinary lockstitch sewing machines is to form and set each individual stitch before the thread is drawn through the work for the succeeding stitch. This necessitates the use of a thread measuring finger to engage the needle thread between the needle and the work to provide thread for one side of the needle loop as the needle retracts through the work. In sewing machines of the rotary horn type, however, there is no room available in the tip of a horn of practical size for accommodating, in addition to the customary needle threading whirl, a thread finger for measuring a supply of thread between the needle and the work and for releasing the thread as the threaded needle retracts through the work.

Accordingly, with this type of machine it has been the usual practice to arrange and actuate the stitch-forming devices in such a manner that, during the formation of each stitch, a loop of needle thread is left projecting from the work from which thread is drawn by the needle during its retracting stroke, the final drawing of the loop into the work to set the stitch being accomplished either by the needle or by the shuttle as the needle loop last drawn through the work by the needle is passed over the shuttle. Where this method of handling the thread has not been followed, it has been necessary to use an undesirably large needle in order to permit the thread to reeve freely through the needle hook as it withdraws through the work. A more definite object of the present invention, therefore, is to provide mechanism in a McKay type shoe sewing machine by which each stitch may be formed and set, preferably by a needle thread take-up, before the needle acts to draw a loop of thread through the work for a new stitch, without employing an undesirably large needle or a horn having a tip of greater size than will fit within the toe of a small sized shoe.

An important feature of the invention, with these objects in view, contemplates the provision in a straight hook needle sewing machine having a rotatable horn of ordinary tip dimensions, of a needle looper in the horn mounted to move toward and from the tip of the horn, and a thread finger mounted at a distance from the tip of the horn for measuring a supply of thread between the needle and the work in order that each stitch may be formed and set in the work before the formation of the next stitch has been commenced.

An additional feature of the invention which, while intended primarily for use with the type of looper described, may be employed with any needle threading device mounted to rotate with a shoe supporting horn, contemplates the provision of mechanism for turning the needle during each needle reciprocation in accordance with the rotary movement of the horn, so as to present the barb of the needle in position for proper action of the needle threading device in the horn.

Other features of the invention include the use of a rotary cam shaft in the horn for operating the reciprocating needle looper in order to reduce the length and mass of the reciprocating parts; connections including a system of differential gearing for operating the cam shaft in proper relation to the reciprocation of the needle; means for preventing a needle rotation sufficient to entangle the loop of needle thread as it is drawn from the work; and the devices, combinations and arrangements of parts hereinafter described and claimed, certain of which, while adapted for use in sole sewing machines of the McKay type, are also capable of use with other types of sewing machines.

The several features of the present invention and the advantages obtained thereby will be readily understood by those skilled in the art from the following description taken in connection with the accompanying drawings which illustrate an embodiment of the invention.

In the drawings, Fig. 1 is a view in side elevation of the complete machine; Fig. 2 is a view in vertical section on an enlarged scale of the shoe supporting horn illustrating the mechanism therein; Figs. 3 and 4 are detail views of a portion of the needle looping mechanism with the parts shown in two different positions; Fig. 5 is a view on a still larger scale of the tip portion of the horn shown in Figure 2, indicating the needle in looping position; Fig. 6 is a perspective view of the needle looper; Fig. 7 is a perspective view of the thread finger for laying the thread

across the end of the looper; Fig. 8 is a perspective view of the thread finger supporting arm; Fig. 9 is a view in front elevation of the sewing head of the machine; Fig. 10 is a view in side elevation of a portion of the sewing head, looking from the right; Fig. 11 is a view in side elevation of the sewing head of the machine looking from the left; Fig. 12 is a perspective view of a portion of the mechanism for maintaining the needle in proper angular relation with the other sewing devices, the parts being separated to more clearly illustrate the construction; Fig. 13 is a view in front elevation of a part of the mechanism shown in Fig. 12; Figs. 14 and 15 are, respectively, a side sectional view and a view from the rear of a locking device cooperating with the mechanism shown in Fig. 12; Figs. 16 to 20 inclusive are detail sectional plan views taken on a plane passing through the hook portion of the needle and illustrating the movements of the needle into its various angular positions; Figs. 21 to 25 inclusive are detail sectional views showing respectively the positions assumed by certain parts of the needle controlling mechanism corresponding to the positions of the needle indicated in Figs. 16 to 20; Fig. 26 is a view in front elevation, partly in section, showing the take-up mechanism and thread clamps for the needle thread; Fig. 27 is a view in side elevation of the take-up mechanism and thread clamps shown in Fig. 26, a part of the casing and the wax pot being shown in section; Fig. 28 is a sectional plan view on an enlarged scale, of the thread locks and a portion of the mechanism for operating them in positions assumed on stopping the machine; Fig. 29 is a detail view of a part of the mechanism shown in Fig. 28, looking from the left; Fig. 30 is a detail view of a part of the mechanism shown in Fig. 28 looking from the right; Figs. 31 and 32 are fragmentary views of portions of the thread lock operating mechanisms taken along the line 31—31 of Fig. 28, and illustrating successive stages of operation; Fig. 33 is a sectional view taken on the line 33—33 of Fig. 11, looking from the front of the machine; Fig. 34 is a view in front elevation of a portion of the shuttle and the loop spreader actuating mechanisms; Figs. 35, 36 and 37 are views on an enlarged scale of portions of the needle looper and the thread finger in their respective positions after successive movements of the machine; Fig. 38 is a fragmentary view indicating the horn, needle and loop spreader in their respective positions as the needle withdraws from the work with the loop of thread; Fig. 39 is a diagrammatic view showing the relative relations of the take-up and the thread locks during the sewing operation while the needle loop is passing over the shuttle; Fig. 40 is a similar view showing the parts as the stitch is being set; and Fig. 41 is a view showing the same parts just before the machine stops with thread of the final stitch not drawn into the work.

The lockstitch shoe sewing machine herein illustrated is similar in many respects to that disclosed in the application of Fred Ashworth, Serial No. 394,770, filed September 24, 1929 for Sewing machines on which Patent No. 1,914,936 issued June 20, 1933. The driving mechanism for the sewing shaft, the treadle and connections for driving and disconnecting the sewing shaft, and the mechanism for feeding the work, are substantially the same as described in the application. A great many of the parts common to the two machines are illustrated in the accompanying drawings, but inasmuch as they are fully il-

lustrated and described in the above application, they will be only briefly referred to in the following description.

The illustrated machine is driven from an electric motor 12 through a clutch mechanism indicated in Fig. 1 in dotted lines. This clutch mechanism is controlled from a foot treadle 14 which is normally held in raised position by means of a spring 16. The clutch mechanism acts to connect and disconnect the motor with a shaft 18 and a sleeve 20 in the base of the machine, from which motion is transmitted to a vertical shaft 22 extending up to the sewing head of the machine. Rotation of the shaft 22 imparts a corresponding movement to a sewing shaft 24 for operating the needle, shuttle and other related parts.

The shoe to be operated upon is supported on an angular horn 26 having an inclined upper portion enclosing needle threading devices. Motion is imparted to the needle threading devices through a hollow vertical shaft 28 connected through suitable gears to a horizontal shaft 30 and the vertical shaft 22 driven from the motor 12.

The sewing head of the machine is shown in Figs. 9, 10 and 11, and is provided with a straight hook needle 32, a presser foot 34, a loop taker in the form of a shuttle 36, to carry the needle loop over the bobbin or locking thread, a feed point 37 and a loop spreader 38 which is adapted to spread the needle loop to facilitate its engagement by the shuttle.

As described, in the Ashworth application, the needle 32 is secured in a needle holder 39 at the lower end of a needle bar 40 mounted to reciprocate in bearings 42 and 44 to and from the work in a vertical direction. The needle bar 40 is reciprocated from a crank pin 46 on the end of the sewing shaft 24, through connections which are adapted to permit the needle to be disconnected from its driving mechanism at the top of its retracting stroke. The parts comprising these connections include a needle actuating lever 48 which is secured to the forward end of a rock shaft 50, and is connected through a link 52 to a block 54 connected to the needle bar 40. Also, at the forward end of the rock shaft 50 is a lever 56 loosely fulcrumed at the side of the lever 48, and a continuous reciprocatory movement is imparted to the lever by the engagement of the crank pin 46 in a cam groove 58 in the lever 56. The lever 48 is caused to oscillate with the lever 56 through a resilient connection comprising a coil spring 60 carried on the shaft 50 and connected at its ends to the lever 56 and the shaft 50, respectively. The spring 60 tends to move the needle actuating lever 48 upwardly with the cam lever 56. During the operation of the machine, these levers are further held against independent movement with relation to each other by means of a latch 62 which is pivotally mounted at the end of the needle lever 48. This latch is so constructed that it cooperates at its upper end with a locking lever 64 to cause it to be engaged or disengaged at its lower end from a pin 66 at the end of the crank operated lever 56. The locking lever is fixed at one end of a shaft 67 and provided with an angular slot 68 to receive a cam roll 70 secured to the end of the needle actuating lever 48. The upper end of the slot 68 being offset, the needle actuating lever will be permitted to move freely up and down while the locking lever is held in a position to the right, but will be held out of operation at the top of its retracting stroke while the lock- 75

ing lever is in the position shown in Fig. 9. The movement of the locking lever 64 to locking position also moves the latch 62 away from the pin 66 on the crank operated lever 56, so that the sewing shaft may continue to rotate without operating the needle.

The presser foot 34 is secured to a block 72 on the lower end of a vertically movable presser foot bar 74, and is forced downwardly against the work by means of a spring 76 coiled about the presser foot bar, and also by a spring 78 (see Fig. 11) surrounding and being secured at one end to a shaft 80, and at the other end to an adjustable collar 82 on the machine. The spring 78 acts upon the shaft 80 to move an arm 83 fast on the end of the shaft. The arm 83 is connected to the block 72 at the end of the presser foot bar, so that the pressure exerted by the spring 78 may be adjusted according to the position of the collar 82. The presser foot bar is raised against the tension of these springs by mechanism described more fully in the above referred to application, and including a cam lever 84 (see Fig. 33) loosely fulcrumed on a fixed shaft 86 and provided with a cam roll 88, a cam 90 on the sewing shaft 24, a spring 92 (see Fig. 11) surrounding the shaft 86 and tending to hold the cam roll 88 in engagement with the cam 90, a link 94 connected between the arm 83 and an arm 96 secured to a rock shaft 98, an arm 100 secured to the other end of the rock shaft 98, a pin 102 extending from the arm 100, and mechanism attached to a bracket 104 rigidly secured to the presser foot bar 74. The mechanism on the bracket 104 maintains contact with the pin 102, causing the pin to release the presser foot by a uniform amount regardless of the thickness of the work during each stitch-forming cycle while the work is being fed through the machine.

The feeding mechanism acts through the feed point 37 which is clamped in a carrier 106. The carrier is slidably mounted for vertical movement toward and away from the work in a guide frame 108 which is pivotally mounted on the machine. The frame is oscillated to impart feeding movements to the feed point by a feed lever 110 in the form of a bell crank loosely mounted on the hub of the needle locking lever 64. The vertical arm of the feed lever is provided at one end with a slot 112 engaging the roll 70 on the end of the needle actuating lever 48 to impart an oscillatory movement to the lever, and its horizontal arm has a block and slot connection with an arm of the frame 108. Movements of the feed point 37 toward and away from the work are imparted through connections from the shaft 98 for actuating the presser foot lifting lever. These connections include a bell crank lever 114 connected to the feed point carrier 106 by a link 116, a link 118 pivoted to the other end of the bell crank 114, and an arm 120 secured to the presser foot lifting shaft 98. The feed point is therefore operated to feed the work in timed relation with the raising and lowering of the presser foot so that the feeding operations may take place when the work is released from the pressure of the presser foot. The usual hand lever 122 is also provided for rocking the shaft 98 and manually releasing the presser foot.

The loop spreader 38 is operated across the path of the needle in substantially the same manner as described in the above noted application, being secured at the end of a carrier 124 (see Fig. 10) pivotally mounted on parallel links 126. The rearward link of the pair is provided with a cam

roll engaging a cam 128 mounted to oscillate with a shaft 130 journalled in a bracket on the machine. The shaft 130 (see Fig. 34) is operated by an arm 132 fast to the shaft and connected at its outer end to a downward extension from the needle actuating lever 48 by an adjustable link 134. As thus far described, the machine does not differ materially from the machine disclosed in the prior application above referred to.

The principal feature of the present invention relates to the provision of a thread measuring looper mechanism within the horn 26, the usual needle threading whirl, having been replaced by a comparatively thin forked looper, indicated at 136, mounted in a slideway extending along the upper inclined portion of the horn for reciprocation toward and from the upper end of the horn. The upper end of the horn is constructed with the usual needle opening 138 to permit the needle to enter the horn in receiving the thread, and in the illustrated embodiment of this feature of the invention, the needle looper 136 is operated to move from a retracted position to a position in which a portion of thread extending across its forked end is carried beyond the needle opening 138 as indicated in Fig. 5. After the needle has entered the horn, the needle looper 136 retracts in laying the thread within the barb of the needle, the needle at this time, as will be described, facing with its open hook in a direction corresponding to the direction in which the upper portion of the horn is pointed. The thread, indicated at 140, extends downwardly through a passage 142 (see Fig. 37) in one side of the looper, then over pulleys 144 and 146 rotatably mounted in the horn (see Fig. 2) and downwardly through the hollow vertical shaft 22 to a source of supply 148 (see Fig. 1). To provide a length of thread between the needle and the looper 136, a thread measuring finger 150 is arranged to move across the end of the looper as the looper is advanced toward the tip of the horn. The thread finger 150 is in the form of a lever and is carried upon a lever arm 154 pivotally mounted at its lower rear end on a pin 158 secured in the frame of the horn. The thread finger at its upper forward end is provided with a downwardly extending right angle portion 162, which when actuated relatively to the looper after the looper has returned from the upper end of the horn, engages the thread extending from the passage 142 in the looper to form a bight in the thread at one side of the looper. The pivot pin 158 about which the thread finger carrying arm 154 swings is arranged so that a swinging movement of the arm about its pivot, while the looper is advancing, will carry the downwardly extending portion 162 of the thread finger across the path of the looper from one side of the looper to the other at a fixed distance from the tip of the horn, and during this movement the thread is engaged with the forked ends of the looper, as indicated in Figures 3, 4, 35, 36 and 37. To actuate the thread finger in the proper time relation to the reciprocating movements of the looper, the lever arm 154 is provided with a cam follower 159 which engages a suitably shaped cam slot 160 formed in the looper, the arrangement being such that as the looper advances towards the tip of the horn the thread finger is actuated to lay the thread across the forked end of the looper, as indicated in Figure 36, and then during the continued forward movement of the looper, the thread finger remains stationary and the required amount of thread is drawn from the supply, as indicated in Figure 37. In order to re-

lease the bight of thread held by the thread finger, the thread engaging end of the thread finger is moved upwardly across a projection 164 of the horn (see Figures 2 and 5), thereby sweeping the thread from the thread finger. To permit the thread finger to be moved in this manner, it is pivotally mounted midway its length in the lever arm 154 by means of a horizontal pivot pin 155 engaging a bearing in the lever arm. The thread arm is held securely against lateral movement with relation to the lever arm 154 by a tongue 156 at the forward end of the lever arm which engages a vertical slot 157 formed on the thread finger.

In order to reciprocate the looper, a continuously rotating cam disk 166 is mounted on a shaft 167 fixed in the lower portion of the horn. The cam disk is provided with a cam slot 168 on one face from which movement is imparted to a bell crank 170 pivoted on a short shaft 171 secured in the horn. The lever 170 is provided at its lower end with a cam roll engaging the cam slot 168 and at its upper end with an enlargement 172, fitting within a correspondingly shaped opening 174 at the lower end of the looper 136. To move the thread finger lever across the projection 164 in the horn to release the thread, a downwardly and rearwardly extending arm of the thread finger lever is provided with a stud 176 engaging a slot 178 formed in a cam disk 180 rotatably mounted in an intermediate part of the horn. The cam disk 180 is formed on its outer surface with gear teeth meshing with corresponding teeth at the upper end of a rack rod 182 provided at its lower end with an opening to receive an enlarged end 184 of a second bell crank 186. The bell crank 186 is pivotally mounted on a shaft 188 fixed in the horn and a downwardly extending arm of the bell crank carries a cam roll engaging a second slot 169 in the cam disk 166.

The cam 168 for operating the thread finger and looper is rotated by an angularly disposed hollow helical gear 190 meshing with gear teeth on the outer edge of the cam 166. The hollow gear 190 is formed with an integral hub 192 rotatably mounted in a sleeve 194 secured in the horn. Within the hollow of the gear 190, an internal gear 191 is formed meshing with a planetary gear 196 rotatable on a stud 192 eccentrically mounted on a bevel gear 200. The bevel gear 200 is mounted for rotation outside a sleeve 202 secured within the frame of the horn, and meshes with a corresponding gear 204 attached to the upper end of the hollow vertical shaft 28. Rotation of the shaft 28 imparts a corresponding movement to the bevel gear 200 through the gear 204 and rotates the looper and thread finger operating cam 166 through the planetary gear 196 and the hollow gear 190.

The horn 26 is mounted on the machine to rotate a complete turn of 360 degrees, and is provided with a downwardly extending hollow spindle 212 having ball bearings 214 between the upper and lower ends of the spindle and the frame of the machine. The shaft 28 is journaled within the spindle 212 to rotate about an axis concentric with the axis of rotation of the horn, which coincides with the longitudinal axis of the needle.

To prevent rotation of the horn about its bearings in the machine from effecting the position of the cam 166 for operating the needle looper and thread finger, relative to the position of the needle in its reciprocating movement toward and away from the horn, a differential system of gearing is provided comprising a ring gear 216 formed integrally with the machine

frame, a bevel gear 218 with which the gear 216 meshes attached to the lower end of a spindle 220 rotatable within the sleeve 202, a gear 222 fixed to the upper end of the spindle 220 and the planetary gear 196 with which the gear 222 meshes. This system of gearing causes the planetary gear to normally revolve about the gear 222. The position of the gear 222, however, will change as the horn is turned, thereby correcting the position of the gear 191 which meshes with the planetary gear 196 in accordance with any movement imparted to the bevel gear 200 by reason of the rotation of the horn about the driving gear 204.

In the machine described in the Ashworth application above referred to which employs a needle threading whirl at the tip of the horn, the whirl is continuously rotated to lay the thread within the hook of the needle. This whirl is driven through shafts and gearing to cause the whirl to turn uniformly through the same angle of rotation with respect to the needle while the lower end of the needle is positioned within the horn. The system of gearing for connecting the driving shafts to the needle whirl is so arranged that the needle whirl remains stationary while the machine is stopped even though the horn is turned about its mounting on the machine. Through this system of gearing the rotation of the horn does not interfere in any way with the operation of the needle threading whirl. In the machine illustrated herein, in which the looper is mounted in the upper inclined portion of the horn to reciprocate towards and away from the tip of the horn in laying the thread within the hook of the needle, the looper must necessarily be rotated with the horn. Consequently, in order to lay the thread with certainty within the hook of the needle, mechanism is provided for turning the needle before it enters the horn to a uniform angular position with respect to the horizontal component of movement of the needle looper in the horn, so as to cause the needle hook to face in the same direction with respect to the line of feed as the direction in which the upper portion of the horn is inclined. Such a position, for purposes of illustration, is shown at 32a in Figure 38 in which the needle has been turned 90 degrees. The turning movement imparted to the needle is varied according to the angular position of the horn by connections between the horn and the needle turning mechanism. These connections are operated from the spindle 212 of the horn, as will be hereinafter described.

The mechanism for turning the needle is illustrated in the left portion of Figure 12, in which the upper end of the needle bar 40 is shown as being in the form of an elongated pinion 224 meshing with a rack 226. Movement of the rack in one direction or the other causes the needle bar 40 to rotate by a corresponding amount without effecting the reciprocating movement. In order to permit free rotation of the needle reciprocating bar, the bracket 54 (see Fig. 9) connected to the needle actuating lever 48 is formed with a central opening in which a block 228 is mounted between horizontal surfaces of the bracket, and is clamped securely on the needle reciprocating bar 40. The needle bar is thus permitted to rotate as well as to reciprocate in its bearings on the machine.

During its upward stroke, the needle is returned to a fixed angular position in which it presents the needle loop properly to the loop spreader and the other thread handling devices, this position

being indicated at 32b in Figure 38. As a convenient means for timing the rotations of the needle properly with relation to the reciprocating movements of the needle, the rack 226 of the needle turning mechanism is actuated through suitable connections from the needle actuating lever 48. These connections, as has been indicated, are controlled by the rotary movements of the horn.

The rack 226 for rotating the needle is formed at its ends with upturned curved portions. The left hand curved portion is pivotally mounted on an arm 230 fulcrumed on a pin 232 fixed in the frame of the machine. The rack 226 is guided at its lower left end within a slot formed in an intermediate part of the arm 230. The right hand curved portion of the rack 226 is pivotally mounted on a pin 234 carried on an upwardly extending arm of a bell crank 236. The lower right end of the rack is guided in a slot in the bell crank 236, similar to that in the arm 230. The bell crank 236 is secured to a horizontal shaft 238 having bearings in the frame of the machine, and is operated by an arm of the needle actuating lever 48 through a pair of inter-connected links 240 and 242, one link being pivotally connected at 244 to said arm, indicated at 246, extending from the needle actuating lever 48, and the other link being pivotally connected at 248 to a downwardly extending arm of the bell crank 236. The two links are connected together by a third pivot pin 250.

The link 240 is slotted at its ends and both links 240 and 242 are cut away at their central portions so that they may lie closely together with their pivots 244 and 248 in alignment with each other at one limit of the movement of the actuating arm of the needle lever. In order to support the link 240 more rigidly, an arm 252 extends from the hub of the lever 48 to overlap the outer edge of the link 240 and the pivot 244 is divided between the arms 246 and 252. A sufficiently large clearance space is thus provided between these two arms to permit the pivot 250 to be swung freely within the hub of the lever 48 into any position in the recess so formed.

The needle is turned by the rack 226 engaging the pinion 224 in one direction as the needle actuating lever operates to move the needle toward the work and is turned in the other direction as the hook of the needle withdraws from the horn, so that the hook of the needle will assume the proper angular position to receive successfully the thread from the needle looper and, upon its retracting stroke to present properly the loop of needle thread to the loop spreader and shuttle. The pivotal connection 250 of the links 240 and 242 is supported at the lower end of a link 256, the upper end of which is mounted upon a pivot pin 260 at the outer end of an arm 258 projecting from a hollow shaft or sleeve 262 surrounding the shaft 238. The pivotal connection 250 of the links 240 and 242 thus moves about the pivot pin 260 as a center when the links are actuated to reciprocate the needle rotating rack 226. As the needle actuating lever 48 is oscillated to actuate the needle, the needle rotating rack 226 will be actuated through the links 240 and 242 from the arm 246 on the hub of the needle actuating lever, and it will be apparent from an inspection of Figures 12 and 13 that the extent of the movement imparted to the rack will depend upon the position or path of movement of the pivotal connection 250 of the links with relation to the pivotal axis of the needle actuating lever or, in other words, of the axis of the shaft 50. It will also be

obvious from an inspection of these figures that the direction of rotation of the needle during its downward movement will depend upon which side of the axis of the shaft 50 the pivotal connection 250 or its path of movement is located. The position of the pivotal connection 250 is controlled from the horn spindle through connections hereinafter described, acting to shift the position of the arm 258 carrying the pivot supporting link 256.

The manner in which the rotation of the needle is controlled by adjusting the position of the pivotal connection 250 of the links 240, 242 will be more clearly understood from an inspection of Figures 16 to 25 inclusive which indicate various angular positions of the needle at the limit of its downward stroke, together with the corresponding position of the pivotal connection 250. As indicated in Figure 16, the needle at the limit of its downward stroke has rotated through a few degrees only in a counter-clockwise direction and, during its upward stroke, will rotate through a few degrees in a clockwise direction as indicated by the arrow a, to bring the needle to the position marked zero, which is its position at the upward limit of its stroke. To cause the needle to assume the position indicated in Figure 16 at the limit of its downward stroke and to rotate in the direction of the arrow a during its upward stroke, the pivotal connection 250 has been adjusted to the position indicated in Figure 21. To decrease the amount of rotation imparted to the needle, the pivotal connection 250 is adjusted in a direction indicated by the arrow b in Figure 21. When the pivotal connection 250 is brought into alignment with the axis of the shaft 50, as indicated in Figure 22, no movement of rotation will be imparted to the needle during its downward and upward movements, and the needle will assume the position indicated in Figure 17 at the limit of its downward stroke. To cause the needle, during its downward stroke, to rotate a few degrees in a clockwise direction to the position indicated in Figure 18, and during its upward stroke to rotate in a counter-clockwise direction 45 to its original position, as indicated by the arrow a, the pivotal connection 250 is moved to the position indicated in Figure 23. Continued movement of the pivotal connection 250 in the direction indicated by arrow b on Figure 23, will increase the amount of rotation imparted to the needle in a clockwise direction during its downward movement. With the construction illustrated in the drawings, the limit of such movement is reached when the pivotal connection 55 250 reaches the position indicated in Figure 24. With the pivotal connection in this position, the needle, at the limit of its downward stroke, will assume the position indicated in Figure 19 and, during its upward stroke, will rotate in the direction of the arrow a through nearly 180 degrees to its original position. By moving the pivotal connection 250 in the direction indicated in Figure 24, by arrow b, the rotation of the needle in a clockwise direction during its downward stroke 65 will be gradually decreased to zero and after the pivotal connection passes the axis of the shaft 50, the needle will be rotated in a counter-clockwise direction during its downward movement, the extent of which rotation will increase until it has 70 reached nearly 180 degrees, as indicated in Figure 20, at which time the pivotal connection 250 will be in the position indicated in Figure 25.

The rearward end of the hollow shaft 262 is provided with an arm 264 connected with a sec- 75

ond arm 266 by a link 268. The second arm 266 is fixed to a rock shaft 270 journalled in the main frame. The rock shaft 270 is operated from the horn 26 through an arm 272 fixed to the rear end 5 of the shaft, a link 274 pivotally connected at one end to the arm 272 and at the other end to a cam lever 276 (see Figs. 1 and 2) and a cam block 278 fixed by screws 280 to rotate with the horn spindle 212. The lever 276 is fulcrumed on a 10 shaft 277 in the frame of the machine and the outer arm of the lever is provided with a cam roll 282 engaging a cam slot 283 in the cam block 278. This cam slot is formed throughout its major portion with a constant gradual pitch and with a 15 steep return portion for rapidly moving the cam lever 276 from one extreme position to the other. Rotation of the horn, therefore, causes the link 274 to move gradually in one direction or the other until the steep return portion of the cam is 20 reached, at which time the link is quickly shifted from one extreme position to the other. A corresponding movement is imparted to the rock shaft 270 which, through the arm 266, link 268, arm 264, shaft 262 and arm 258, tends to move 25 the pivot pin 250. A complete rotation of the horn, therefore, swings the pin 250 from one of the positions shown in Figures 24 and 25 to the other and then, through a quick return movement, back again.

30 In order to prevent entanglement of the thread from too great a turning movement of the needle as it moves away from the horn with the thread loop, the mechanism for turning the needle is so constructed that the threaded needle 35 will not rotate in one direction through an angle of greater than substantially 180 degrees. To limit the turning movement of the needle, the cam block 278 connected to the horn is so adjusted with relation to the horn that in a position 40 of the horn in which the cam roll 282 at one end of the lever 276 cooperates with the central part of the constant pitch portion of the cam slot 283 (see Fig. 2), no turning movement is imparted to the needle. The quick return portion 45 of the cam slot 283 then is approximately 180 degrees in either direction from this neutral position of the cam follower. This adjustment causes the needle turning mechanism to rotate the needle approximately 180 degrees in either 50 direction from a position in which no turning is imparted to the needle.

As the cam roll 282 enters the steep return portion of the cam slot 283, the position of the pivot 55 pin 250 in the needle turning mechanism is shifted from one extreme position to the other, as shown in Figures 24 and 25. In the absence of other devices to be described, if the horn were held in the position in which the cam roll 282 remained in the steep return position of the cam slot 283, 60 the needle, when at the limit of its downward stroke, would not face in the proper direction to receive the loop from the looper. Accordingly, a second series of connections is arranged between the needle turning mechanism and the 65 horn for preventing a shift in the path of movement of the pivot pin 250 by the connections which have just been described while the cam roll 282 engages the steep return portion of the cam 278. To permit the horn to be turned at 70 this time, the connections between the horn and the needle turning mechanism for controlling the position of the pivot pin 250 are permitted to yield in either direction. For this purpose the connection between the arm 266 on the shaft 75 270 and the arm 264 on the hollow shaft 262

comprising the link 268 is arranged to yield in both directions. The link 268 is formed with a straight rod portion and is provided with a shoulder 286 near its point of pivotal connection 288 with the arm 266. At the other end, the link is 5 threaded and a pair of lock nuts 290 form an adjustable shoulder. A spring 284 is enclosed within a sleeve 292 formed at one end with a pair of oppositely disposed bosses 291. Pivot pins for connection with the arm 264 pass through openings in lugs of the arm 264 and engage corresponding recesses in the bosses 291 of the sleeve 292. The spring 284 is compressed between shoulders formed on a pair of collars 294 sliding at opposite ends of the rod portion of the link 10 15 268 so that as the link is shifted, pressure is exerted through one of the shoulders at the ends of the link through the collar 294 at the other end of the link and against the spring in either direction, depending upon the movement of the arm 266. As shown in Fig. 12, the spring is being compressed by movement of the arm 266 in the direction of the arrow. The right end of the sleeve 292 is closed by a shoulder 293 and the 20 left end by a nut 296 threaded into the sleeve, 25 providing means for limiting the movement of the spring in either direction.

A shift in the path of movement of the pivot pin 250 to vary the action of the needle turning mechanism while the cam roll 282 is in the steep return portion of the cam slot 283 is prevented by means of a latch lever 298 fulcrumed on a pin 300 secured within a lug 302 formed integrally with the sleeve 292. The rearward end of the shaft 238 carries a slotted disk 304 fixed to oscillate with the shaft as the shaft is operated with the needle turning mechanism. The slot of the disk 304 is formed at its opposite ends with two latching edges 306 and 308 for engagement with two latching projections 310 and 312, respectively, projecting from one end of the latch lever 298. During the engagement of the cam roll 282 and the steep return portion of the cam slot 283, one or the other of the projections 310 and 312 are caused to engage the latching edges 306 and 308, respectively, to arrest the movement of the sleeve 292. Further rotation of the horn thereafter produces no movement of the pivot pin 250 until the latch 298 is released, as hereinafter described, causing the pivot pin 250 to 40 move substantially instantaneously from one extreme position to the other, and causing the needle turning mechanism to impart as a result, a reverse turning movement to the needle from that previously imparted during a given needle 45 stroke.

The latch 298 for thus restraining the needle turning mechanism against variation of needle rotation is moved to latching position by a spring 314 coiled about the hub of the lever and tensed between one end of the lever and the sleeve 292. The latch 298 is held in inactive position, out of contact with the latching edges of the disk 304 against the action of the spring 314 during the major part of a complete horn rotation by the 50 previously mentioned second series of connections to the horn, which will now be described.

The second series of connections acting between the needle turning mechanism and the horn controls the latch lever 298 through the 55 movement of a collar 316 loosely surrounding the sewing shaft 24 (see Figs. 9 and 12). The collar 316 is provided with a roll 318 mounted for rotation in a slot formed in the collar. The roll 318 is located to engage the end of the latch 60 65 70 75 80 85 90 95 100

lever 298 when the collar 316 is rotated in the direction of the arrow shown in Fig. 12. This movement raises the end of the latch lever to separate the latching projections 310 and 312 from the disk 304 in which position the latch is maintained throughout the greater portion of horn rotation. The collar 316 is moved by a gear segment 320 fixed to the forward end of a shaft 322 in a position to mesh with teeth formed on one side of the collar 316. The shaft 322 is mounted to oscillate in the frame of the machine and carries at its rearward end an arm 324 pivotally connected to a vertical link 326. The lower end of the link 326 is connected to a cam lever 328 pivotally mounted on the shaft 277 with the lever 276, and arranged to cooperate with a second cam slot 330 which is formed in the cam block 278. The cam slot 330 is shaped to cause the latch 298 to be released into latching position by the roll 318 during the time in which the cam roll 282 engages the steep return portion of the cam slot 283 so that the latch lever 298 will, during this interval, engage one latching edge of the disk 304 and prevent variation of the turning movement of the needle.

To cause the latch 298 to release the needle turning mechanism so that the shift of the pivot pin 250 from one extreme position to the other will take place at the upper part of the needle stroke in which part there is little or no turning movement imparted to the needle, the outer end of the latch 298 is engaged by a releasing lever 332 mounted to oscillate about a pivot 334 fixed in the frame of the machine. The upper end of the lever 332 is formed with a slot through which the latch lever extends and the latch is engaged by a cross piece 336 forming the upper end of the slot. When the horn is slowly rotated in one direction beyond the point where the steep return portion of the cam slot 283 acts on the cam roll 282 and to a position where the collar 316 is turned in the direction of the arrow, the latch releasing lever 332 is moved about its pivot 334, in the direction indicated in Fig. 12, by a link 338 pivotally connected to the collar at one end and passing loosely through an opening in the lower end of the releasing lever 332. Movement is imparted to the lever 332 by the link 338, through a spring 340 compressed between a shoulder on the link 338 and the lower end of the releasing lever, and the movement of the spring is limited by a pair of lock nuts 342 threaded on the end of the link 338. The latch releasing lever 332 first engages a vertical edge formed on the latch 298, which in the position illustrated in Fig. 12, is the vertical edge of the projection 312. The maximum amount of oscillation will, under these conditions, be imparted to the shaft 238 by the needle turning mechanism, and according to the extreme position of the pivot pin 250 of the mechanism shown in Figs. 12 and 25 with the needle moving downwardly, the latching disk 304 is being rotated by the shaft 238 in the direction of the arrow on the disk. As this motion continues, the latching edge 308 of the disk 304 moves the latch 298 downwardly until the cross piece 336 on the latch releasing lever 332 escapes the projection 312 and moves under the influence of the spring 340, to a position in which the cross piece 336 lies directly over the projection. The needle bar 48 then begins to rise, and the disk 304 is rotated in the opposite direction, causing the latching edge 308 to permit the projection 312 to rise against the cross piece 336 of the latch releasing lever. Continued movement in

this direction moves the latching edge 308 of the disk away from the projection 312, and upon release of the latch, the spring 284 acts to snap the pivot 250 of the needle turning mechanism from the position shown in Fig. 12 to the opposite extreme position shown in Fig. 24. The parts are so adjusted as to cause this release at the upper part of the needle stroke where the needle is always returned to a fixed angular position with respect to the other stitch-forming devices.

From the position of the horn in which the pivot pin 250 occupies the other extreme position, indicated in Fig. 24, movement of the horn in the opposite direction from that indicated above causes the projection 310 to engage the latching edge 308 of the disk 304, restraining the needle turning adjusting mechanism, and as the collar 316 is rocked in the direction of the arrow, pressure of the spring 340 against the latch releasing lever 332 causes the cross piece 336 of the latch releasing lever to engage the vertical edge of a projection 344 at the extreme end of the latch lever 298. On account of the position of the pivot pin 250 with relation to the axis of the shaft 238 of the needle turning mechanism, the shaft 238 is being operated in a reverse direction with respect to the reciprocating movement of the needle, so that as the needle descends toward the horn the shaft 238 rotates in a direction reverse from that indicated by the arrow in Fig. 12. This causes the latching edge 308 of the disk 304 to be disengaged from the projection 310 in substantially the same way as in the case of engagement of the projection 312 with the latching edge 308, previously described. Otherwise the releasing operation of the latch 298 is accomplished in the manner previously indicated.

As a further assurance against variation in the degree of rotation imparted to the needle by the needle turning mechanism throughout the lower portion of the needle stroke, a second restraining device is connected to the mechanism for turning the needle, and provided with means for locking the needle turning mechanism against variation of needle rotation. This mechanism comprises a slotted link 346 pivotally connected to the pin 260, and a locking member 348 slidably secured in a portion of the machine frame (see Figs. 9, 12, 14 and 15). The locking member 348 is forced against the locking link 346 by a comparatively heavy spring 350 surrounding a shank portion of the locking member 348, and engaging at its ends a shoulder on the locking member and a hollow nut 352 threaded into an opening in the machine frame. The spring 350 is of sufficient strength to lock the pivot pin 250 in position through frictional engagement of the locking member with the locking link. The locking link 346 is maintained in position against the pressure of the spring 350 by a bracket 354 fastened to the frame of the machine by bolts 355. The locking member 348 is released from engagement with the locking link 346 by longitudinal movement of a shaft 356 which is mounted for reciprocation in an enlarged portion of the bracket 354 and engages at one end the slot of the locking link. The central portion of the shaft 356 is threaded and engages a nut 358 carried in a slot of the bracket. The nut 358 is rotated during each reciprocating movement of the needle by an arm 360 clamped to the nut 358 by a bolt 362 passing through the arm 360. The arm is operated by the needle actuating lever 48 through a link 364 engaging a threaded hole in a rotatable stud 366 passing loosely

through the outer end of the nut operating arm 360. The link 364 is pivotally mounted at its other end on the pivot pin 244 carried by the arm 246 of the needle actuating lever 48. When the 5 needle moves upwardly with the needle actuating bar 48, the link 364 swings the lever 360 in a counter-clockwise direction as viewed in Fig. 15, causing the shaft 356 to be forced against the locking member 348 through the slot in the locking link 346, to compress the spring 350 and release the locking link for unrestricted movement. Rotation of the shaft 356 in the bracket 354 is prevented by a lug 370 extending from the shaft within a slot in the bracket 354. When the 10 needle has reached a position at the upper portion of its stroke where little or no rotation is imparted to the needle, the locking member 348 is disengaged from the locking link 346, so that the link may slide, and the tension of the spring 20 284 may act to shift the position of the pivot 250 of the needle actuating mechanism. By means of this locking device, any variation of the position of the pivot 250 by reaction against rotary movement of the needle bar 48 is prevented.

25 In order to allow sufficient time for the needle turning mechanism to act properly, the needle is permitted to remain at the upper portion of its stroke during a greater period of time than in the machine of the Ashworth application, and 30 for this reason the cam groove 58 formed within the crank actuated lever 56 has been arranged to permit a dwell in the reciprocating movement of the needle during the upper portion of the needle stroke.

35 It is desirable that the thread be passed around the shuttle 36 in as short a time as possible after the needle has reached the upper portion of its stroke, and to accomplish this, operating connections directly to the sewing shaft 24 (see Fig. 34) have been provided, comprising a cam 372, an oscillating member 374 provided with parallel internal surfaces 376 engaging the cam 372, a lever 378 loosely fulcrumed on the shaft 130 which carries the loop spreader operating 40 cam and an adjustable link 380 pivotally connected between an arm of the member 374 and an arm of the lever 378. The other arm of the lever 378 is formed with a gear segment 382 engaging a gear 384 attached to the end of a shaft 50 which carries the shuttle 36. The member 374 is formed with an internal stud 386 projecting parallel to the sewing shaft 24, and journaled in the frame of the machine, so that as the cam 372 on the sewing shaft rotates, it oscillates the 55 member 374 about the stud 386.

60 As has been stated, a feature of the invention relates to a thread lock for gripping the thread to set the stitch uniformly through the action of the take-up. The thread lock and take-up are illustrated in Figure 26, in which the thread lock, hereinafter referred to as the sewing thread lock, is indicated at 388, and the take-up at 390. The needle thread 140 passes from the supply 148, and through a tension device 392 of ordinary construction provided with an adjustable tension nut 394 for varying the amount of tension, thence around a shaft 396 carrying the thread lock 388 loosely journaled in a bracket 398 attached to the machine, downwardly 65 through a wax pot 400 of ordinary construction, upwardly over a pulley 402 carried by the bracket 398, downwardly around a pulley 404 at the end of the take-up lever 390 through a pulley 406 on the bracket 398, and upwardly into the 70 horn, as previously described. In order to pre-

75 vent entanglement of the thread about the end of the take-up lever, the pivot about which the pulley 404 at the end of the take-up rotates is provided with an elongated spindle 407 (see Fig. 27) extending from the axis of the pulley at right angles to the line of movement of the take-up. The take-up 390 is operated from a cam 408 carried by the horizontal shaft 30 which forms a part of the operating connections to the needle threading devices in the horn. The take-up is 10 fulcrumed on a shaft 410 provided with a headed portion and secured on a bracket 412 attached to the machine frame. Thread drawing and surrendering movements are imparted to the take-up through connections between the take-up and a cam slot 414 formed in the cam 408, which connections include a bell-crank 416 formed with a sleeve portion 418 fulcrumed on a shaft 420 secured to the frame of the machine, and a link 422 connected between the take-up 20 lever and one end of the bell crank. The other end of the bell-crank carries a cam roll 424 engaging the cam slot 414. One end of the link 422 is pivotally mounted on the take-up lever 390, and the other end is loosely pivoted on a stud 25 426 clamped within an adjusting slot in the bell-crank. The sleeve 418 of the bell-crank is loosely mounted on the shaft 420, and is prevented from displacement by a collar 428 clamped at the end of the shaft. The thread lock 388 is actuated 30 to grip the thread between the take-up and the supply during each thread drawing stroke of the take-up as it reaches the lower portion of its stroke. The thread tension 392 offers sufficient resistance to cause the take-up, in moving from 35 the position indicated in Figs. 26 and 39, to draw a loop of needle thread from the shuttle toward the work. As the needle loop approaches the work, it engages the locking thread indicated at 430, and draws it against the work. Thereafter, 40 the resistance offered by contact of the thread with the work exceeds the resistance offered by the thread tension, so that a supply of thread is drawn through the tension before the take-up reaches the end of its thread drawing stroke. 45 Just before the end of the take-up stroke is reached, the thread lock 388 is applied, and further movement of the take-up draws the needle loop a uniform distance into the work against the thread lock 388, as shown in Fig. 40. Thus, the 50 three operations of drawing the needle loop against the work, measuring thread from the supply, and setting the stitch, are accomplished during a single stroke of the take-up.

55 A thread lock 388 is actuated to grip the thread just before the needle thread take-up 390 reaches the end of its thread drawing stroke by a cup-shaped cam 432, shown in Fig. 28, adjustably secured in a recess in the cam 408 by a set screw 433, a lever 434 having a cam roll 436 at one end 60 arranged to engage the cam 432, the shaft 396 which supports the thread lock 388, a spring 437 surrounding the shaft and a block 438 secured to the shaft 396 by a set screw 440 (see Fig. 28). The thread lock 388 is formed as a washer movable toward and from a shoulder 442 formed on a sleeve 444 surrounding the shaft 396 and loosely fitting within an opening in the bracket 398. The shaft 396 is mounted in the bracket 398 to both oscillate and move freely in a longitudinal direction. The lever 434 is clamped by means of a bolt 446 to the shaft 396 to oscillate the shaft when the cam roll 436 is engaged by the cam 432. The block 438 is provided with a pair of projections 448 to cooperate with a similarly shaped recess 75

450 contained in a block 452 mounted on the bracket 398 and is resiliently pressed by the spring 437 compressed between the block 438 on the shaft 396 and a washer 456 thrusting against the bracket 398 to cause the thread lock 388 to grip the thread against the shoulder 442. As the shaft 396 is oscillated by the cam 432, the projections 448 rise part way out of the recesses 450, moving the shaft 396 longitudinally to release the thread at the proper time to allow the take-up to measure thread during its thread drawing stroke. The cam 432 is so proportioned that the time in which the cam roll 436 is released to move under the action of the spring 437 and the projections 448 enter the recesses 450 occurs just before the take-up has completed its stroke. In order to adjust the timing, the block 452 (see Fig. 29) is adjustably secured to the bracket 398 by a bolt 457 slidably arranged in a slot in the bracket.

20 In accordance with another feature of the invention, in order to simplify the act of severing the thread at the end of a seam, the loop of needle thread of the final stitch is positively prevented from being drawn into the work and is held in a position shown in Fig. 41, through the action of a second thread lock 458, hereinafter referred to as the final stitch thread lock. This second thread lock comprises a washer mounted loosely on a shaft 460 to be moved, in gripping the thread, 25 toward and from a shouldered sleeve 462 surrounding the shaft. The sleeve 462 is loose on the shaft 460 and slides freely in a longitudinal direction in an opening in the bracket 398 but is held 30 against angular rotation by a pin 464 projecting from the bracket 398, and passing through a slotted projection at one side of the sleeve 462.

In order to operate the second thread lock 458 effectively to grip the thread, it must act during the thread drawing stroke of the take-up 399, 40 and for this purpose the shaft 460 is operated by a cam 466 secured to the end of the shaft 30. The shaft 460 carries an arm 468 fixed to its inner end which is provided with a cam roll 470 in position to be acted upon by the cam 466. The shaft 460 is loosely mounted in the bracket 398, and is moved longitudinally by the action of a spring 472 surrounding the central part of the shaft. The spring is compressed between a block 474 clamped by a set screw 476 to the shaft and a washer 478 thrusting against the bracket 398. The block 474 is provided with a pair of projections 480 cooperating with similarly shaped recesses 482 in a block 484 secured to the bracket 398, to impart a longitudinal movement against the action of the spring 472 as the shaft is oscillated by the cam 466. This longitudinal movement causes the thread lock 458 to move toward and from the sleeve 462 to grip the thread in timed relation with the operation of the take-up. The thread lock thus operates to grip the thread between the take-up and the work as the thread is being drawn toward the work by the take-up, preventing the take-up from drawing the last formed needle thread loop and the locking thread against the work. To adjust the timing of the second thread lock, the block 484 is adjustably secured to the bracket 398 (see Fig. 30) by a bolt 481 passing through a slot in the bracket.

In order to prevent the thread lock 458 from acting to grip the needle thread during each stitch-forming cycle of the machine, the sleeve 462 is provided with a pair of diametrically opposite recesses 486 to cooperate with projections 488 formed on a collar 490. The collar 490 is loosely mounted on the sleeve 462, and is provided with

gear teeth 491 (see Fig. 26) meshing with a segmental gear 492 extending from the hub of a lever 494 loosely mounted on the sleeve 444. During normal operation of the machine, the collar 490 assumes a position different from that shown in Fig. 28, and in which the projections 488 coincide with the recesses 486 on the shouldered sleeve 462, so that the space between the thread lock washer 458 and the shoulder of the sleeve is greater than the thickness of the thread. As a result, the thread is free of the lock at all times during the sewing of a seam. As the machine is brought to rest, the projections 488 are moved out of the recesses 486 to the positions shown, and the thread is gripped by the thread lock, permitting the needle loop to remain above the surface of the work.

It is necessary during the time in which the final stitch thread lock 458 acts, to prevent the application of the sewing thread lock 388, as otherwise the thread would be broken by the take-up. For this purpose, connections operated during the completion of the final stitch as the machine is brought to rest, operate to release the sewing thread lock 388 from engagement with the shoulder 442, and permit the application of the final stitch thread lock 458, and finally to release the thread lock 458 from the sleeve 462, simultaneously with the release of the needle thread tension, so that the work may be withdrawn a short distance from the machine before severing the thread. These connections for actuating the thread locks in their proper sequence during the completion of the final stitch are operated by a stop mechanism which is of substantially the same construction as that described in the application of Ashworth Serial No. 418,- 35 545, filed January 4, 1930.

The stop mechanism which is rendered operative when it is desired to bring the machine to rest acts to disconnect the needle from its actuating mechanism and lock it out of operation at the top of its retracting stroke as above described, and to raise the presser foot from engagement with the work as well as to actuate the thread locks and tension device in the manner just indicated. When the foot treadle 14 is released, it allows the needle locking lever 64 to move to the left under the influence of a spring 496 (see Fig. 33) coiled about one end of a shaft 498, and secured at one end to the shaft and at the other end to the frame of the machine. The shaft 498 is journaled in the machine frame and carries at the end opposite the spring 496, an arm 500 rigidly mounted thereon. An arm 501 is rigidly mounted on the shaft 498 and is connected to the treadle 14 by a link 504. This arm is provided with a projection 503 extending beneath a rearward extension of the arm 500 and engaging said rearward extension upon the release of the treadle. The arm 500 is connected to the shaft 67 to which the needle locking lever 64 is fixed by a link 506 connected to the arm 500 at one end and at the other end to an arm 508 fixed to the shaft 67, which connections cause the needle to be disconnected from the sewing shaft 24 when the treadle is released. Release of the foot treadle also acts to swing an arm 509 attached at the rearward end of the locking lever shaft 67 in a counter-clockwise direction as viewed in Fig. 33. The arm 509 extends downwardly, and loosely supports a pin 510 at its lower end. The pin 510 is perforated at its ends, and a pair of links 512 and 514 extend through the openings thus formed. These links

are connected to a presser foot lifting member 516 and a retaining member 518, respectively, loosely suspended at their upper ends from the sewing shaft 24. The member 518 is provided with an eccentric strap 520 surrounding an eccentric member 522 on the sewing shaft 24, but the hook member 516 is supported loosely on the shaft itself, so that no movement is imparted to it by rotation of the shaft. When the shaft 67 is rocked in a direction to disconnect the needle from the sewing shaft at the end of a seam, the lifting member 518 is moved toward the right by the arm 509 against one arm of a T-shaped lug 524 projecting laterally from an arm of a lever 526 loosely mounted on the shaft 83 which carries the presser foot lifting arm 83. The shaft 83 being rotatably mounted in the machine, is provided at its rearward end with an arm 528 secured to the shaft and arranged with a portion 530 overlying the lug 524. This movement, of course, occurs only after the motor has been disconnected from the machine, the sewing shaft continuing to rotate under the momentum of the rotating parts. As the shaft continues to turn, the hook 518 is forced beneath the lug 524 by a spring 532 surrounding the link 514. Further rotation of the sewing shaft acts to raise the lug 524 and rock the lever 526 and the shaft 67 to raise the presser foot. At the same time an outwardly extending arm of the lever 526 moves downwardly to operate the thread locks 388 and 458 through a second lever 536 (see Fig. 1) and a link 538 connecting the two levers. The lever 536 is fulcrumed on a bolt 540 threaded into the frame of the machine, and is formed with openings 542 and 544 for engagement with enlargements 546 and 548, respectively (see Fig. 28) formed at the ends of the levers 434 and 494, in the order stated, for operating the thread locks. The lever 536 is maintained in a position in which the sewing thread lock acts to grip the thread by a spring 549 connected to the machine frame, and the lever carries a pair of set screws 550 and 552 entering within the opening 542 to adjust the relative movement between the lever 536 and the sewing thread lock lever. As the stop mechanism begins its operation, lever 526 (see Fig. 33) in the head of the machine begins its movement by the presser foot lifting member 516 and the sewing thread lock operating lever 434 is rocked with the shaft 396 to release the sewing thread lock 388. This movement also moves the lever 494, rotating the projections 488 out of the recesses 486, so that as the take-up draws the final needle loop towards the work, the thread lock 458 will be operated to grip the thread, and the thread lock 388 will be held in released position. The position of the lever 434 under these circumstances is shown in Fig. 31, in which the adjusting screw 552 is shown as rocking the lever 434 to a position in which the sewing thread lock 388 is released. In order to release the final stitch thread lock 458 as the main sewing shaft 24 continues to rotate, the lever 434 is rocked into the position shown in Fig. 32, and a lug 554 formed on the lever 434 engages a finger 556 on the arm 468, causing the lever 468 to be operated away from a position in which the final stitch thread lock 458 grips the thread. At the same time that the thread locks are released, the tension on the thread is also released by a downwardly extending arm of the lever 536 (see Fig. 1) and a rod 560 pivotally connected to the arm of the lever. The forward end of the rod carries a perforated

enlargement 562 which bears against the tension 392, and guides the thread between the tension and the supply. At the end of the stop mechanism operation, the lever 536 is moved and the rod 560 releases the thread from the tension, so that the work may be withdrawn from the machine without resistance. 5

The parts thus operated are retained in position by the action of the retaining member 518 engaging the lug 524, a spring 568 which surrounds the link 512 acting to prevent release of the retaining member 518 while the sewing shaft is brought to rest and until the treadle 14 is again depressed. 10

As the machine is started by movement of the treadle 14, the shaft 498 is rocked in a reverse direction, and the retaining member 518 is released from the lug 524 against the action of the spring 568, by an arm 570 carrying a roll fixed to the shaft 498 and engaging a cam surface on the retaining member 516. The presser foot lifting member 518 is also retracted from engagement with the lug 524 by movement of the arm 508 and the shaft 67 as the treadle is depressed. In order to retract the presser foot lifting member 516, the link 514 connecting the lifting member with the pin 510, is provided with a pin 572 passing through the end of the link which projects through the opening in the pin 510, so that as the arm 508 moves the pin 510, it engages the pin 572 in the link 514, and operates the lifting member 516. 15 20 25 30 35

In order to facilitate replacement of the needle 32 in the needle holder 39 at the lower end of the needle bar 40, the upper needle bar bearing 42 is slotted and provided with a manually operated clamp bolt 574 (see Figs. 9, 10, and 11), by which the needle bar 40 may be secured in fixed position in the machine while the needle holder is manipulated to release the needle and another 40 needle adjusted in place. 35

Certain features of the machine herein disclosed relating more particularly to the take-up and the thread locks and other devices cooperating with the take-up form the subject-matter of 45 a divisional application Serial No. 729,617 filed June 8, 1934.

The nature and scope of the invention having been indicated, and an embodiment of the invention having been specifically described, what 50 is claimed is:

1. A lockstitch shoe sewing machine having, in combination, stitch-forming devices including a straight hook needle, a loop taker, a rotatable horn arranged to extend within a shoe, a needle looper mounted in the horn for reciprocation toward and from the tip of the horn to advance a portion of thread into position to loop the needle, a thread finger mounted in the horn with its thread engaging portion at a distance from 60 the tip of the horn for measuring thread between the work and the looper, and means for swinging the thread finger across the end of the looper as the looper moves toward the tip of the horn. 65

2. A lockstitch shoe sewing machine having, in combination, stitch-forming devices including a straight hook needle, a loop taker, a rotatable horn arranged to extend within a shoe, a needle looper mounted in the horn for reciprocation toward and from the tip of the horn to advance a portion of thread into position to loop the needle, a thread finger mounted in the horn with its thread engaging portion at a distance from 70 the tip of the horn, and means for swinging the thread finger across the end of the looper and 75

thereafter for holding the thread finger stationary at the side of the looper as the looper moves toward the tip of the horn to measure thread between the work and the looper as the looper advances toward the horn tip.

5. A lockstitch shoe sewing machine having, in combination, stitch-forming devices including a straight hook needle, a loop taker, a rotatable horn arranged to extend within a shoe, a needle looper mounted in the horn for reciprocation toward and from the tip of the horn to advance a portion of thread into position to loop the needle, and a thread finger pivoted in the horn with its extremity at a fixed distance from the tip of the horn for measuring thread between the work and the looper, a projection in the horn adjacent the end of the thread finger, and means for swinging the thread finger across the projection to release the measured thread as the needle 10 is retracted from the horn.

6. A lockstitch shoe sewing machine having, in combination, stitch-forming devices including a straight hook needle, a loop taker, a rotatable horn arranged to extend within a shoe, a needle looper mounted in the horn for reciprocation toward and from the tip of the horn, an arm pivoted to the horn, a thread finger pivoted to the arm for movement about an axis at right angles to the pivot axis of said arm, and a cam shaft 15 and suitable connections for reciprocating the looper and actuating the thread finger about its pivot on the arm, and a cooperating cam and follower connection between the looper and the arm for swinging the thread finger with the arm 20 across the end of the looper.

7. A lockstitch shoe sewing machine having, in combination, stitch-forming devices including a straight hook needle, a loop taker, a rotatable horn arranged to extend within a shoe, a forked needle looper mounted in the horn for reciprocation toward and from the tip of the horn to advance a portion of thread into position to loop the needle and provided with a thread 25 passage extending in the direction of reciprocation, a thread finger pivoted in the horn with its extremity at a fixed distance from the tip of the horn, a projection in the horn adjacent the end of the thread finger, and means for actuating the thread finger across the path of the thread 30 extending between the thread passage at the forked end of the looper and the work, and thereafter across the projection to release the measured thread as the needle is retracted from the horn.

8. A lockstitch shoe sewing machine having, in combination, stitch-forming devices including a straight hook needle, a loop taker, a rotatable horn arranged to extend within a shoe, a needle looper mounted for movement toward and from the tip of the horn and formed with a forked portion at its forward end to surround the end of the needle in looping position, a thread finger pivoted in the horn with its thread engaging end at a distance from the horn tip, means for actuating the thread finger to lay a portion of thread across the forward end of the looper as the looper advances toward the tip of the horn, and operating connections for actuating the stitch-forming devices in timed relation to retract the looper from the tip of the horn in laying the thread within the hook of the needle.

9. A lockstitch shoe sewing machine having, in combination, stitch-forming devices including a straight hook needle, a loop taker, a rotatable horn arranged to extend within a shoe, a needle

looper mounted for movement toward and from the tip of the horn and formed with a forked portion at its forward end to surround the end of the needle in looping position, a thread finger pivoted in the horn with its forward end at a distance from the horn tip, a projection in the horn adjacent the end of the thread finger, a cam and follower connection between the thread finger and the looper for actuating the thread finger to lay a portion of thread across the forward end of the looper as the looper advances toward the tip of the horn, a cam shaft for operating the looper and thread finger, and connections for actuating the stitch-forming devices in timed relation to retract the looper in laying the thread 10 within the hook of the needle and to release the thread from the thread finger by swinging the thread finger across the projection as the needle is retracted from looping position.

10. A lockstitch shoe sewing machine having, in combination, stitch-forming devices including a straight hook needle, a loop taker, a rotatable horn arranged to extend within a shoe, a needle looper mounted for movement toward and from the tip of the horn and formed with a forked portion at its forward end to surround the end of the needle in looping position, an arm pivoted to the horn, a thread finger pivoted to the arm for movement about an axis at right angles to the pivot axis of said arm, a cam and follower connection between the thread finger and the looper for actuating the thread finger to lay a portion of thread across the forward end of the looper as the looper advances toward the tip of the horn, a projection in the horn adjacent the end of the thread finger, and a cam shaft for operating the looper and the thread finger to retract the looper in laying the thread within the hook of the needle and to swing the thread finger about its pivot on said arm across the projection as the needle is retracted from looping position.

11. A lockstitch shoe sewing machine having, in combination, stitch-forming devices including a straight hook needle, a loop taker, a shoe supporting horn rotatably mounted in the machine frame and arranged to extend within the shoe, a needle looper mounted in the horn for movement toward and from the tip of the horn, a rotary shaft mounted in the horn, and connections between the rotary shaft and the looper for reciprocating the looper.

12. A lockstitch shoe sewing machine having, in combination, stitch-forming devices including a straight hook needle, a loop taker, a shoe supporting horn rotatably mounted in the machine frame and arranged to extend within the shoe, a needle looper mounted in the horn for movement toward and from the tip of the horn, a rotary shaft mounted in the horn, connections between the rotary shaft and the looper for reciprocating the looper, and an operating shaft extending from the machine frame into the horn for driving said shaft.

13. A lockstitch shoe sewing machine having, in combination, stitch-forming devices including a straight hook needle, a loop taker, a shoe supporting horn rotatably mounted in the machine frame and arranged to extend within the shoe, a needle looper mounted in the horn for movement toward and from the tip of the horn, a rotary cam shaft mounted in the horn, connections between the cam shaft and the looper for reciprocating the looper, an operating shaft extending from the machine frame into the horn for driving the cam shaft, and differential gear-

ing for preventing rotation of the cam shaft due to relative motion between the horn and the operating shaft.

12. A lockstitch shoe sewing machine having, 5 in combination, stitch-forming devices including a straight hook needle, a loop taker, a rotatable shoe supporting horn, a needle looper mounted in the horn for movement toward and from the tip of the horn, a continuously rotating cam shaft mounted in the horn, connections between the cam shaft and the looper for reciprocating the looper, an operating shaft journaled concentrically with the axis of horn rotation for driving the cam shaft, and differential gearing mounted 10 in the horn between the driving shaft and the cam shaft for preventing rotation of the cam shaft due to relative motion between the horn and the operating shaft.

13. A lockstitch shoe sewing machine having, 20 in combination, stitch-forming devices including a straight hook needle, a loop taker, a shoe supporting horn mounted for rotation on the machine frame, a needle looper mounted in the horn for movement toward and from the tip of the horn, a continuously rotating cam shaft mounted 25 in the horn, connections between the cam shaft and the looper for reciprocating the looper, an operating shaft journaled concentrically with the axis of horn rotation for driving the cam shaft, differential gearing mounted in the horn 30 between the driving shaft and the cam shaft, and a gear member provided on the frame of the machine and arranged to mesh with a corresponding member of the differential gearing for preventing rotation of the cam shaft due to relative 35 rotation between the horn and the operating shaft.

14. A lockstitch shoe sewing machine, having, 40 in combination, stitch-forming devices including a straight hook needle, a loop taker, a rotatable shoe supporting horn arranged to extend within the shoe, needle threading mechanism mounted in the horn to turn with the horn, and mechanism for turning the needle about its longitudinal 45 axis to cause the needle hook to face in a fixed direction with respect to the line of feed at the upper portion of the needle stroke and to face in a direction at the lower portion of the needle stroke varying with the angular position of the 50 horn with respect to the line of feed.

15. A lockstitch shoe sewing machine having, 55 in combination, stitch-forming devices including a reciprocating straight hook needle, a loop taker, a rotatable shoe supporting horn arranged to extend within the shoe, needle threading mechanism mounted in the horn to turn with the horn, and mechanism for turning the needle about its longitudinal axis to rotate the needle hook from a fixed angular position with respect to the line 60 of feed into an angular position varying with the angular position of the horn with respect to the line of feed as the needle moves toward the work and for returning the needle to said fixed angular position as the needle is retracted from the 65 work.

16. A lockstitch shoe sewing machine having, 70 in combination, stitch-forming devices including a straight hook needle, a loop taker, a rotatable shoe supporting horn, needle threading mechanism mounted in the horn to turn with the horn, a sewing shaft for reciprocating the needle into and out of operative relation with the horn, mechanism operated from the sewing shaft for turning the needle about its longitudinal axis to rotate the needle hook from a fixed angular 75 position with respect to the line of feed into a second angular position as the needle moves toward the work and for returning the needle hook to said fixed angular position as the needle is retracted from the work, and connections be-

sition with respect to the line of feed into a second angular position as the needle moves toward the work and for returning the needle hook to said fixed angular position as the needle is retracted from the work, and connections between 5 the horn and the needle turning mechanism operable by rotation of the horn for varying the second angular position assumed by the needle hook as it enters the horn.

17. A lockstitch shoe sewing machine having, 10 in combination, stitch-forming devices including a straight hook needle, a loop taker, a rotatable shoe supporting horn arranged to extend within the shoe, needle threading mechanism, mechanism for turning the needle about its longitudinal 15 axis, and means for controlling said needle turning mechanism to cause the turning movement after the needle is threaded to be imparted in one direction or the other depending on the angular position of the horn. 20

18. A lockstitch shoe sewing machine having, 25 in combination, stitch-forming devices including a straight hook needle, a loop taker, a rotatable shoe supporting horn arranged to extend within the shoe, needle threading mechanism mounted 25 in the horn to turn with the horn, and mechanism for turning the needle in one direction about its longitudinal axis during one part of the rotary movement of the horn from a position in which the needle hook faces in a fixed direction with 30 respect to the line of feed at the upper portion of the needle stroke to a position in which the needle hook faces in a direction at the lower portion of the needle stroke varying with the angular position of the horn with respect to the line 35 of feed, and for imparting a similar turning movement to the needle in the other direction during the remaining part of a complete horn rotation.

19. A lockstitch shoe sewing machine having, 40 in combination, stitch-forming devices including a straight hook needle, a loop taker, a rotatable shoe supporting horn arranged to extend within the shoe, needle threading mechanism mounted in the horn to turn with the horn, a sewing shaft 45 for reciprocating the needle into and out of operative relation with the horn, a rock shaft arranged to be oscillated by the sewing shaft, a second shaft spaced from said rock shaft, mechanism connected to the second shaft for turning 50 the needle about its longitudinal axis, an arm on each of said shafts, pivotally interconnected links connecting said arms, and means for shifting the path of the pivotal interconnection of 55 said links to one side of the axis of said rock shaft while the horn is being turned through approximately 180 degrees and to the other side of the axis of said rock shaft while the horn is being turned through the remaining part of a complete rotation. 60

20. A lockstitch shoe sewing machine having, 65 in combination, stitch-forming devices including a straight hook needle, a loop taker, a rotatable shoe supporting horn, needle threading mechanism mounted in the horn to turn with the horn, a sewing shaft for reciprocating the needle into and out of operative relation with the horn, mechanism operated from the sewing shaft for turning the needle about its longitudinal axis to rotate the needle hook from a fixed angular 70 position with respect to the line of feed into a second angular position as the needle moves toward the work and for returning the needle hook to said fixed angular position as the needle is retracted from the work, and connections be- 75

between the horn and the needle turning mechanism for varying the second angular position with respect to the line of feed of the needle hook as it enters the horn, one of said connections comprising a resilient element for permitting the horn to move independently of the needle turning mechanism.

21. A lockstitch shoe sewing machine having, in combination, stitch-forming devices including a straight hook needle, a loop taker, a rotatable shoe supporting horn, needle threading mechanism mounted in the horn to turn with the horn, a sewing shaft for reciprocating the needle into and out of operative relation with the horn, mechanism operated from the sewing shaft for turning the needle about its longitudinal axis to rotate the needle hook from a fixed angular position with respect to the line of feed into a second angular position as the needle moves toward the work and for returning the needle hook to said fixed angular position as the needle is retracted from the work, connections comprising a resilient element between the horn and the needle turning mechanism for varying the second angular position of the needle hook as it enters the horn and a locking device acting on said connections to prevent variation of the second position of the needle.

22. A lockstitch shoe sewing machine having, in combination, stitch-forming devices including a straight hook needle, a loop taker, a rotatable shoe supporting horn arranged to extend within the shoe, needle threading mechanism mounted in the horn to turn with the horn, a sewing shaft for reciprocating the needle into and out of operative relation with the horn, a rock shaft arranged to be oscillated by the sewing shaft, a second shaft spaced from said rock shaft, mechanism connected to the second shaft for rotating the needle about its longitudinal axis, an arm on each of said latter shafts, pivotally interconnected links pivoted to be oscillated, each to one of the arms of the respective shafts, and means for shifting the path of the point of pivotal interconnection of said links with respect to the axis of said rock shaft as the horn is turned on the machine.

23. A lockstitch shoe sewing machine having, in combination, stitch-forming devices including a straight hook needle, a loop taker, a rotatable shoe supporting horn arranged to extend within the shoe, needle threading mechanism mounted in the horn to turn with the horn, a sewing shaft for reciprocating the needle into and out of operative relation with the horn, mechanism operated from the sewing shaft for turning the needle about its longitudinal axis to rotate the needle hook from a fixed angular position with respect to the line of feed into a second angular position as the needle moves toward the horn, a cam having an active surface of gradual pitch and a steep return surface connected for rotation with the horn, connections comprising a resilient element between the cam and the needle turning mechanism for varying the second angular position of the needle hook, and means for restraining movement by the connections of the needle turning mechanism while the horn is turned through that part of a rotation in which the steep return surface of the cam acts on said connections.

24. A lockstitch shoe sewing machine having, in combination, stitch-forming devices including a straight hook needle, a loop taker, a rotatable shoe supporting horn arranged to extend within the shoe, needle threading mechanism mounted

in the horn to turn with the horn, a sewing shaft for reciprocating the needle into and out of operative relation with the horn, mechanism operated from the sewing shaft for turning the needle about its longitudinal axis to rotate the needle hook from a fixed angular position with respect to the line of feed into a second angular position as the needle moves toward the horn, a cam having an active surface of gradual pitch and a steep return surface connected for rotation with the horn, connections comprising a resilient element between the cam and the needle turning mechanism for varying the second angular position of the needle hook, a detent for restraining movement by the connections of the needle turning mechanism by causing the resilient element to yield, and means for releasing the detent after the horn is turned through that part of a rotation in which the steep return surface of the cam acts on the connections to said needle turning mechanism and after the needle has reached the end of its stroke in moving out of operative relation with the horn.

25. A lockstitch shoe sewing machine having, in combination, stitch-forming devices including a straight hook needle, a loop taker, a rotatable shoe supporting horn arranged to extend within the shoe, needle threading mechanism mounted in the horn to turn with the horn, a sewing shaft for reciprocating the needle into and out of operative relation with the horn, mechanism operated from the sewing shaft for turning the needle about its longitudinal axis to rotate the needle hook from a fixed angular position into a second angular position as the needle moves toward the horn, a block having a cam surface of gradual pitch with a steep return portion connected for rotation with the horn, connections comprising a resilient element between the cam block and the needle turning mechanism for varying the second angular position of the needle hook, a detent for restraining movement by the connections of the needle turning mechanism by causing the resilient element to yield, a second shaft connected to the needle turning mechanism for oscillation in unison with the reciprocation of the needle, a second cam surface in said cam block, and means operated in part by said second shaft and in part by said second cam surface for releasing the detent after the needle has been retracted from the work and after the horn is turned through that part of a rotation in which the steep return portion of the cam surface acts on the connections to said needle turning mechanism.

26. A lockstitch shoe sewing machine having, in combination, stitch-forming devices including a straight hook needle, a loop taker, a rotatable horn arranged to extend within a shoe, a needle looper mounted for movement toward and from the tip of the horn and formed with a forked portion at its forward end to surround the end of the needle in looping position, a thread finger pivoted in the horn with its thread engaging end at a distance from the horn tip, means for actuating the thread finger to lay a portion of thread across the forward end of the looper as the looper advances toward the tip of the horn, and mechanism for turning the needle about its longitudinal axis to cause the needle hook to face in a fixed direction with respect to the line of feed at the upper portion of the needle stroke and to face in a direction at the lower portion of the needle stroke varying with the angular

position of the horn with respect to the line of feed.

27. A lockstitch shoe sewing machine having, in combination, stitch-forming devices including 5 a straight hook needle, a loop taker, a rotatable horn arranged to extend within a shoe, a needle looper mounted for movement toward and from the tip of the horn and formed with a forked portion at its forward end to surround the end 10 of the needle in looping position, a thread finger pivoted in the horn with its thread engaging end at a distance from the horn tip, means for actuating the thread finger to lay a portion of thread across the forward end of the looper as the looper 15 advances toward the tip of the horn, and mechanism for turning the needle in one direction about its longitudinal axis during one part of the rotary movement of the horn from a position in which the needle hook faces in a fixed direction 20 with respect to the line of feed at the upper portion of the needle stroke to a position in which the needle hook faces in a direction at the lower portion of the needle stroke varying with the angular position of the horn with respect to the line of feed and for imparting a 25 similar turning movement to the needle in the other direction during the remaining part of a complete horn rotation.

28. A lockstitch shoe sewing machine having, 30 in combination, stitch-forming devices including a reciprocating straight hook needle, a loop taker, a rotatable shoe supporting horn arranged to extend within the shoe, needle threading mechanism mounted in the horn to turn with the horn, 35 and mechanism for turning the needle about its longitudinal axis to rotate the needle hook in timed relation to the reciprocating movement of the needle and a connection from the horn to the needle turning mechanism for changing the 40 direction of needle rotation as the horn is turned on the machine.

29. A lockstitch shoe sewing machine having, in combination, stitch-forming devices including 45 a reciprocating straight hook needle, a loop taker, a rotatable shoe supporting horn arranged to extend within the shoe, needle threading mechanism mounted in the horn to turn with the horn, and mechanism for turning the needle about its longitudinal axis to rotate the needle hook in timed relation to the reciprocating movement of the needle, connections from the horn to the needle turning mechanism for changing the direction of needle rotation and for varying the degree of rotary movement imparted to the 50 needle, and other connections from the horn to the needle turning mechanism for causing the direction of rotation of the needle to be changed substantially instantaneously as the horn reaches a predetermined rotary position.

30. A lockstitch shoe sewing machine having, 55 in combination, stitch-forming devices including a reciprocating straight hook needle, a loop taker, a rotatable shoe supporting horn arranged to extend within the shoe, needle threading mechanism mounted in the horn to turn with the horn, mechanism for turning the needle about its longitudinal axis to rotate the needle hook in timed relation to the reciprocating movement of the needle, connections including a resilient 60 element from the horn to the needle turning mechanism for changing the direction of needle rotation and varying the degree of rotary movement imparted to the needle, other connections from the horn to the needle turning means for 65 causing the direction of rotation of the needle 70 75

to be changed as the horn reaches a predetermined rotary position, and means for locking the needle turning means against movement by the first connections as the horn is turned through a part of its rotation.

31. A lockstitch shoe sewing machine having, 5 in combination, stitch-forming devices including a reciprocating needle bar, a needle holder at one end of the needle bar for releasably holding a needle, a rotatable shoe supporting horn arranged to extend within the shoe, needle threading mechanism mounted in the horn to turn with the horn, mechanism for turning the needle bar about its longitudinal axis to rotate the needle holder from one angular position to another varying with the angular position of the needle looper in the horn, and a securing device for maintaining the needle bar in fixed position during replacement of the needle in the needle holder.

32. A McKay type shoe sewing machine having, in combination, stitch forming devices including a straight hook needle, a shoe supporting horn rotatably mounted in the machine frame and arranged to extend within the shoe, a needle 10 threading looper mounted in the horn for movement toward and from the tip of the horn, a thread finger in the horn arranged to form a bight of thread between the looper and the work, and connections operated from without the horn 15 20 25 30 during replacement of the looper and thread finger.

33. A McKay type shoe sewing machine having, in combination, stitch forming devices including a straight hook needle, a shoe supporting horn rotatably mounted in the machine frame and arranged to extend within the shoe, a needle threading looper mounted in the horn for movement toward and from the tip of the horn, a thread finger in the horn arranged to cooperate with the looper to form a bight of thread between the looper and the work, and connections operated from without the horn for actuating the looper to form with the thread finger a bight in the thread and thereafter to loop the needle.

34. A McKay type shoe sewing machine having, in combination, stitch forming devices including a straight hook needle, a shoe supporting horn rotatably mounted in the machine frame and arranged to extend within the shoe, a needle threading looper mounted in the horn for movement toward and from the tip of the horn, a thread finger in the horn arranged to form a bight of thread between the looper and the work as the looper advances towards the tip of the horn, and connections operated from without the horn 40 45 50 55 60 for actuating the looper to form with the thread finger a bight in the thread, and thereafter to loop the needle.

35. A McKay type shoe sewing machine having, in combination, stitch forming devices including a straight hook needle, a shoe supporting horn rotatably mounted in the machine frame and arranged to extend within the shoe, a needle threading looper mounted in the horn for movement toward and from the tip of the horn, a thread finger in the horn arranged to cooperate with the looper to form a bight of thread between the looper and the work, means to release the thread from the thread finger, and connections operated from without the horn for actuating the looper to form a thread bight with the thread finger, to loop the needle and to release the thread from the thread finger.

36. A McKay type shoe sewing machine having, in combination, stitch forming devices in-

- cluding a straight hook needle, a shoe supporting horn rotatably mounted in the machine frame and arranged to extend within the shoe, a needle threading looper mounted in the horn for movement toward and from the tip of the horn, a thread finger in the horn arranged to cooperate with the looper to form a bight of thread between the looper and the work, connections operated from without the horn for actuating the looper to form with the thread finger a bight in the thread and thereafter to loop the needle, and means operating on said connections for preventing rotation of the horn from changing the position with respect to the horn of the looper. 5
- 10 37. A McKay type shoe sewing machine having, in combination, stitch-forming devices including a straight hook needle, a rotatable horn arranged to extend within a shoe, a needle threading looper mounted in the horn for reciprocation toward and from the tip of the horn to advance thread into position to loop the needle, a thread finger mounted in the horn, and means for relatively actuating the thread finger and looper when the looper has returned from the tip of the horn to form a bight of thread about the thread finger before again advancing the thread into looping position. 15
- 15 38. A McKay type shoe sewing machine having, in combination, stitch-forming devices including a straight hook needle, a rotatable horn arranged to extend within a shoe, a needle threading looper mounted in the horn for reciprocation toward and from the tip of the horn to advance thread into position to loop the needle, a thread finger mounted in the horn at a fixed distance from the tip of the horn to form a bight in the thread between the looper and the work as the looper advances the thread toward the horn tip, and means for actuating the thread finger to release the bight of thread in timed relation to the looping movements of the looper. 20
- 25 39. A McKay type shoe sewing machine hav- 25
- ing, in combination, stitch-forming devices including a straight hook needle, a rotatable horn arranged to extend within a shoe, a needle threading looper having a thread carrying passage at its end mounted in the horn for reciprocation toward and from the tip of the horn to advance the thread into position to loop the needle, a thread finger mounted in the horn at a distance from the tip of the horn for movement transversely to the length of the horn, and means for relatively actuating the thread finger and looper when the looper has returned from the tip of the horn to form a bight of thread about the thread finger and thereafter to retract the thread finger from engagement with the bight of thread. 10
- 30 40. A McKay type shoe sewing machine having, in combination, stitch forming devices including a reciprocating straight hook needle mounted in the machine for rotary movement, a shoe supporting horn mounted in the machine frame to rotate a complete turn of 360 degrees, a needle threading looper mounted in the horn for reciprocation towards and from the tip of the horn, and means for relatively actuating the needle and the looper to ensure looping of the 20 needle in any position of the horn. 25
- 35 41. A McKay type shoe sewing machine having, in combination, stitch forming devices including a reciprocating straight hook needle mounted in the machine for rotary movement, a shoe supporting horn mounted in the machine frame to rotate a complete turn of 360 degrees, a needle threading looper mounted in the horn for reciprocation towards and from the tip of the horn, a thread finger cooperating with the 30 looper to form a bight of thread between the looper and the work, and means for relatively actuating the needle, the looper and the thread finger to ensure looping of the needle in any 35 position of the horn. 40
